US00D847187S

(12) **United States Design Patent** (10) Patent No.: **US D847,187 S**
 Shinozuka (45) Date of Patent: **** Apr. 30, 2019**

(54) **DISPLAY SCREEN OR PORTION THEREOF WITH GRAPHICAL USER INTERFACE**

(71) Applicant: **SHINWA CONTROLS CO., LTD.**, Kawasaki (JP)

(72) Inventor: **Misato Shinozuka**, Kawasaki (JP)

(73) Assignee: **SHINWA CONTROLS CO., LTD.** (JP)

(**) Term: **15 Years**

(21) Appl. No.: **29/633,182**

(22) Filed: **Jan. 12, 2018**

(30) **Foreign Application Priority Data**

Jul. 18, 2017 (JP) 2017-015436

(51) **LOC (11) Cl.** **14-04**

(52) **U.S. Cl.**

USPC **D14/486**

(58) **Field of Classification Search**

USPC D14/485-495

CPC G06F 3/048-3/04897

See application file for complete search history.

(57) **CLAIM**

The ornamental design for a display screen or portion thereof with graphical user interface, as shown and described.

DESCRIPTION

The sole FIGURE shows a display screen or portion thereof with graphical user interface showing my new design. The peripheral dashed broken lines illustrate a display screen or portion thereof and form no part of the claimed design.

The dashed broken lines within the peripheral dashed broken lines illustrate portions of the graphical user interface and form no part of the claimed design.

Shading illustrates tonal contrast.
